UNITED STATES PATENT OFFICE.

CARL SCHEVITZ, OF JACKSONVILLE, FLORIDA.

EXPANSIBLE SHOE-LAST.

1,184,577.

Specification of Letters Patent. Patented May 23, 1916.

Application filed September 8, 1915. Serial No. 49,552.

To all whom it may concern:

Be it known that I, CARL SCHEVITZ, a citizen of the United States, residing at Jacksonville, in the county of Duval and 5 State of Florida, have invented new and useful Improvements in Expansible Shoe-Lasts, of which the following is a specification.

This invention relates to expansible shoe 10 lasts, the object of the invention being to produce a device of the class referred to embodying in connection with a plurality of shoe stretching members movable and operable in different planes, novel means 15 whereby each of said stretching members may be operated independently of the others thereby enabling any desired portion of the upper of a shoe to be stretched to a degree necessary to render the shoe comfortable to 20 a person wearing the same.

The shoe last hereinafter described is adapted to stretch either or both sides of the shoe, or the toe portion thereof either in a substantially horizontal plane or upwardly in relation to the sole of the shoe 25 and the side stretching members are so constructed and mounted relatively to the operating mechanism that they may be adjusted toward and away from the toe of the 30 shoe in order to stretch either or both side portions of the upper at the desired point or points.

With the above and other objects in view, the invention consists in the novel construction, combination and arrangement of parts, 35 as herein described, illustrated and claimed.

In the accompanying drawings:—Figure 1 is a plan view, partly broken away in section, illustrating the expansible shoe last of 40 this invention. Fig. 2 is a vertical longitudinal section on the line 2—2 of Fig. 1. Fig. 3 is a vertical transverse section on the line 3—3 of Fig. 1. Fig. 4 is a vertical transverse section on the line 4—4 of Fig. 1. 45 Fig. 5 is a fragmentary vertical longitudinal section illustrating the pivotal connection of one of the handle bars with the main frame. Fig. 6 is a perspective view of the frame.

50 The expansible shoe last contemplated in this invention comprises a frame designated generally at A and comprising the side frame bars 1, the front cross bar 2, the rear cross bar 3 and the longitudinally extending bars or webs 4 parallel to the side bars 1 and connected at their opposite ex-

tremities to the front and rear bars 2 and 3. The rear cross bar 3 is rounded or arcuate as shown so as to bear internally against the heel portion or counter of the shoe thereby 60 serving to properly position the frame in a shoe.

The longitudinal bars 1 and 2 are provided adjacent to the heel end of the frame with upstanding lugs 5, four of such lugs 65 being shown and two handle bars 6 are pivotally connected to the lugs 5 at 7. Each of the bars 6 is preferably of open rectangular form as best shown in Fig. 4 and has a shaft 8 journaled therein and extending lengthwise thereof, each of said shafts having fast on the upper extremity thereof an operating head shown in the form of a milled wheel 9. At its lower extremity each shaft 8 has fast thereon a pinion 10 the teeth 70 of which are curvilinear and mesh with another pinion 11 fast on the rear end of a countershaft 12 extending longitudinally of the frame 1 and journaled in bearings 13 and 14. The bearing 13 is slidable for a 75 short distance longitudinally of the frame 1, being provided with laterally extending trunnions 15 which move back and forth in guide slots 16 in the main frame. The other bearing 14 may be stationary or mov- 85 able as may be preferred.

On the forward extremity of each shaft 12 there is a bevel pinion 17 which meshes with and drives a bevel gear 18 fast on a sleeve 19 which is slidable in slots 20 ex- 90 tending longitudinally of the frame A. Each sleeve 19 is internally threaded to engage the threaded stem or shank 21 of one of a pair of side stretching members designated generally at B. Each side stretching 95 member comprises a base bar 22 fast on the stem or shank 21 and extending parallel to the adjacent side of the frame A. A pin 23 extends inwardly from the bar 22 and works back and forth in a slot 24 in the 100 frame A to prevent the member B from turning on the axis of the shank or stem 21. Each side spreading member B is formed in cross section as shown in Fig. 3, the same comprising upper and lower plates or sec- 105 tions 25 and 26, respectively, which are connected to the bar 22 by means of a hinge pin 27. Threaded stops or set screws 28 and 29 carried by the bar 22 serve to properly position the plates 25 and 26 in accordance 110 with the upward pressure to be exerted on the upper of the shoe. The stops or screws

28 and 29 are adjusted before the last is inserted in the shoe.

The toe stretching member designated generally at C is constructed in a manner similar to each of the side stretching members B, comprising the upper and lower plates or sections 30 and 31, which are hinged at 32 to an arcuate base bar 33, screws or stops 34 and 35 being employed to properly position the sections 30 and 31. Extending rearwardly from the bar 33 is a stem or shank 36 which is preferably square in cross section as shown in Fig. 3 and is slideable in a guide opening 37 of corresponding shape in the front cross bar 2 of the frame. This prevents the toe spreading member from turning or tilting. The rear end portion of the shank 36 is longitudinally bored and threaded to receive the threaded forward end portion 38 of a shaft 39 journaled in a bearing 40 between the bars or webs 4 and having fast on the rear end thereof a bevel pinion 41 which meshes with and is actuated by a bevel pinion 42 on the lower extremity of an upright shaft 43 journaled in an open rectangular upright or standard 44. The shaft 43 has fast on the upper extremity thereof an operating head 45 shown in the form of a milled wheel.

In operation, after first adjusting the threaded stops or screws 28, 29, 34 and 35, the frame A is inserted in a shoe leaving the operating heads 9 and 45 projecting from the top of the shoe where they are readily accessible. By means of the operating head 45 and the shafts 43 and 39, the toe stretching member C may now be advanced so as to exert any desired pressure within the toe of the shoe. By then operating one of the heads 9, the corresponding side stretching member B may be forced outwardly from the frame so as to exert an outward pressure against the upper. Both of the side stretching members may be forced outwardly by operating both of the heads 9. To adjust the side stretching members B toward or away from the toe of the shoe, the handle bars 6 may be pressed either in a forward or rearward direction, thereby advancing or retracting said side stretching members, enabling the desired portion or portions of the side of the shoe to be stretched in accordance with the shape of the foot to relieve the pressure thereon at the required point. After the shoe has been

stretched, the operations just described are reversed and the expansible shoe last is then withdrawn from the shoe.

Having thus described my invention, I claim:

1. In an expansible shoe last, the combination of a frame, laterally movable side stretching members, and means operable from the exterior of a shoe for independently shifting said stretching members. 65

2. In an expansible shoe last, the combination of a frame, laterally movable side stretching members, a longitudinally movable toe-stretching member, and means operable from the exterior of a shoe for independently shifting each of said side and toe stretching members. 70

3. In an expansible shoe last, the combination of a frame, laterally movable side stretching members, means operable from the exterior of a shoe for independently shifting said stretching members, and means for bodily shifting said side stretching members in a fore and aft direction. 75

4. In an expansible shoe last, the combination of a frame, laterally movable side stretching members, means operable from the exterior of a shoe for independently shifting said stretching members, and means for bodily shifting said side stretching members in a fore and aft direction, each independently of the other. 80

5. In an expansible shoe last, the combination of a frame, a stretching member movable relatively to the frame and embodying a plurality of hinged sections, means for positioning said sections, and means operable from the exterior of the shoe for shifting said stretching member. 95

6. In an expansible shoe last, the combination of a frame, laterally movable side stretching members, means operable from the exterior of a shoe for independently shifting said stretching members, means for bodily shifting said side stretching members in a fore and aft direction, said means including handle bars pivotally connected to the frame, shafts journaled in said handle bars, and longitudinally movable counter-shafts driven by said shafts and geared to said side stretching members. 100

In testimony whereof I affix my signature in presence of a witness.

CARL SCHEVITZ.

Witness:

BENNETT S. JONES.
